UNITED STATES PATENT OFFICE

1,929,136

DISPLAY STAND

William R. Bertels, Kingston, Pa.

Application October 26, 1932. Serial No. 639,702

4 Claims. (Cl. 211—85)

This invention relates to a display stand designed primarily for holding cans and while it is adapted to hold cans of different types it is more especially employed for supporting cans having transparent and/or removable tops whereby the contents can be seen readily and are easily accessible.

Another object is to provide a stand which can be collapsed into a small space when not in use, thereby facilitating storage in packing and/or shipping or storing.

A further object is to provide a stand which is cheap to manufacture, can be easily set up for use, and constitutes an efficient support for the containers placed thereon, there being means for holding the containers positively at the correct angles for display purposes.

With the foregoing and other objects in view which will appear as the description proceeds the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

30 In said drawings

Figure 1 is a front elevation of the stand set up for use, the containers supported thereby being indicated by broken lines.

Figure 2 is a side elevation.

35 Figure 3 is a plan view.

Figure 4 is a front view of the stand collapsed.

Figure 5 is a side view of the collapsed stand.

Figure 6 is a view similar to Figure 2 showing a modified structure.

40 Figure 7 is a section on line 7—7, Figure 6.

Referring to the figures by characters of reference, 1 and 2 designate a pair of standards each of which has a quarter twist near its lower end, as at 3 to provide legs 4 the free terminals of which are bent at right angles to provide feet 5 extending in opposite directions. The upper end of standard 1 is bowed laterally to provide a rounded rest or centering finger 6. This finger is slightly twisted relative to its standard 1 and 50 toward standard 2.

Two pairs of standards 1 and 2 are used and they are pivotally connected at 7 to the side portions of upper and lower frames 8 and 9. These frames, with standards 1 and 2, form parallelograms and the center of the front of each frame

is slightly twisted so as to present a downwardly and rearwardly inclined surface 10. To the lower face of each inclined portion 10 is pivotally connected the upper end of a downwardly and rearwardly inclined bracket or hanger 11 provided at its lower end with an upturned ear 12 forming a stop.

Pivottally connected to standards 1 at 13 are braces 14 each of which has a hole 15 near its free or upper end. The other or front lower end 65 of each brace is formed with a bowed finger 16 similar to fingers 6 these fingers being extended toward each other to provide rounded centering rests for supported container.

Studs 17 are extended laterally from standards 70 2 and when the stand is set up for use these studs extend into the holes 15 in braces 14. Thus the braces, which are diagonally arranged, will hold the stand against collapse. By springing the braces laterally to disengage them from the studs, 75 the frames 8 and 9 and the standards 1 and 2 can be folded compactly, as shown in Figures 4 and 5. The brackets or hangers 11 can be swung laterally about their pivots so as to extend along and substantially parallel with the 80 fronts of frames 8 and 9. Thus the entire device can be folded into a very compact bundle.

To use the stand the parts are unfolded and held by the braces as already explained. Cans C or other containers to be displayed are placed in 85 the stand so that the fronts thereof will rest on hangers 11 and between and upon centering fingers or rests 6 and 16. The front portions of the bottoms of the containers will be supported on the stops or ears 12 while the rear portions 90 of the bottoms will bear against the rear portions of frames 8 and 9 which thus constitute abutments. Thus the containers C will be held in inclined positions with their tops located where they can be seen and reached conveniently. By 95 using transparent or display tops the goods in the containers are easily viewed. If the covers are removable they can be taken off without difficulty. The removed lid or cover L can be temporarily supported by angular brackets 18 attached to the outer sides of one pair of standards 1 and 2 near their upper ends.

Under some conditions it is desirable to support the lower container in a more forward position than the upper container to give more convenient access thereto, to permit proper operation of its lid, and better to expose its contents. For these reasons the modified structure shown in Figures 6 and 7 has been perfected. The upper portion of this device is the same as in the 100 110

form shown in Figures 1 to 5 and is provided with rests 6' and 16'. The bottom frame, however, consists of a rear yoke 19 pivotally connected at 20 to the standards 2' while its sides are lapped by and joined to the sides of a front yoke 21. The free ends of the side yoke 21 are bent toward each other to form supporting ears or abutments 22' and the standards 1' are pivotally connected at 22 to the sides of yoke 21 near the centers thereof. This yoke is extended forwardly beyond the front of the upper frame 8' and in addition to its hanger or bracket 10', has a leg 23 connected thereto. This leg, with the feet of standards 1' and 2' provide a five-point contact 15 with the floor or other supporting surface so that the structure will not tilt under the weight of its load.

The modified device is foldable in the same manner as the other form and the braces 14' 20 serve to prevent collapse when the structure is set up.

By using the modified arrangement the lower can or container C will be supported by ears 22 and hanger or bracket 11' and be positioned forward relative to the upper container. Thus the lower container C is more easily reached, its cover can be raised readily irrespective of its construction, and the contents of said container are fully exposed to the customer. Furthermore as 30 the two containers can be supported in lapped relation as in Figure 6, it is possible to make the device shorter and more compact than the form illustrated in Figure 1.

All standards, braces, frames and hangers can 35 be formed of strips of metal which are easily cut and shaped, so that the entire device is thus very inexpensive to manufacture.

What is claimed is:

1. A display stand including upper and lower 40 frames, opposed pairs of standards pivotally connected to the sides of the frames to form a foldable parallelogram, bracing means for holding the stand against folding, and means carried by and cooperating with each frame for supporting a 45

container in an inclined position in the frame, said means including a container supporting hanger suspended from the front of the frame, and rests carried by the stand above the sides of the frame for centering the supported container. 80

2. A display stand including upper and lower frames, opposed pairs of standards pivotally connected to the sides of the frames to form a foldable parallelogram, bracing means for holding the stand against folding, and means carried by and cooperating with each frame for supporting a container in an inclined position in the frame, said means including a container supporting hanger suspended from the front of the frame, and centering rests bowed inwardly from the upper ends of one standard of each pair and overhanging an adjacent frame at opposite sides of its hanger. 90

3. A display stand including upper and lower frames, opposed pairs of standards pivotally connected to the sides of the frames to form a foldable parallelogram, bracing means for holding the stand against folding, and means carried by and cooperating with each frame for supporting a container in an inclined position in the frame, 95 said means including a container supporting hanger suspended from the front of the frame, and centering rests bowed inwardly from the bracing means and overhanging the adjacent frame at opposite sides of its hanger. 100

4. A display stand including opposed pairs of standards, upper and lower frames extending between and pivotally connected to the standards, said lower frame projecting forwardly beyond the upper frame, means for holding the stand against 110 folding, means depending from the fronts of the frames for supporting containers in inclined positions one in advance of but below the other, portions of said frames constituting abutments for the bottoms of the inclined containers, and a 115 supporting leg connected to the forward end of the lower frame. 105
